UNITED STATES PATENT OFFICE.

JOHN WALKER AND WESTON WALKER, OF BARRE, VERMONT, ASSIGNEES OF ONE-
THIRD TO GEORGE E. MILLS, OF BARRE, VERMONT.

AUTOMATIC SAFETY VALVE TO BE USED ON WATER GAUGES.

Application filed March 5, 1925. Serial No. 13,177.

This invention relates to certain improvements in automatic gauge glass valves and it is an object of the invention to provide a device of this general character which 5 operates to automatically seat or close upon breakage of the glass.

Another object of the invention is to provide a device of this general character with means whereby the valve member may be 10 readily applied in working position.

The invention consists in the details of construction and in the combination and arrangement of the several parts of our improved automatic gauge glass valve where- 15 by certain important advantages are attained and the device rendered simpler, less expensive and otherwise more convenient and advantageous for use, as will be herein- after more fully set forth.

20 The novel features of our invention will hereinafter be definitely claimed.

In order that our invention may be the better understood, we will now proceed to describe the same with reference to the ac- 25 companying drawing, wherein:

Figure 1 is a view partly in elevation and partly in section illustrating a gauge glass valve constructed in accordance with an embodiment of our invention.

30 As disclosed in the accompanying drawings, A and A' denote nipples of desired dimensions having requisite communication with a boiler, the upper nipple A being in communication with the steam arm 1 and the lower nipple A' being in communication with the water arm 2. The connection between each of the nipples A and A' with its coacting arm 1 or 2 is preferably through the medium of the coupling 3. Interposed 35 between and coacting with the arms 1 and 2 in a conventional manner is the glass G and coacting with the arms 1 and 2 in a well known manner are the valves 4.

As herein disclosed, each of the nipples 45 A or A' has its central or intermediate portion formed with a downwardly disposed and substantially V-shaped offset portion 5 the outer end of the bore of which being provided with an internal valve seat 6 with 50 which is adapted to engage a valve member 7 preferably a ball. While this valve mem- ber or ball may be made of any desired ma- terial we find it of essential advantage to form the same from copper. A wall of the 55 portion 5 opposed to the leg a in which the

valve member or ball 7 operates is provided with an opening 8 of a diameter sufficient to permit the ready insertion or application of the valve member or ball 7 within the leg a. This opening 8 is normally closed by a plug 60 9 the outer end of which being provided with a hexagonal head 10 to facilitate the desired application or removal of the plug. The inner face of the plug 9 has extended outwardly therefrom and preferably at its 65 axial center, a pin 11 which serves to limit the extent of movement of the valve member or ball 7 away from its seat 6 so that it will be assured that such valve member at all 70 times will be in a position for effective operation.

It is to be noted that the valve member or ball 7 is of a diameter slightly less than the major diameter of the bore of the leg a in which it is arranged. This is particu- 75 larly desirable in the lower nipple A' as it permits sufficient passage of water in the event the conventional pet cock should be employed in connection with the water arm 2.

In the event the glass G should break, the 80 boiler pressure will cause the valve mem- bers or balls 7 to engage their seats 6 sub- stantially instantaneously and with an au- 85 tomatic operation.

While the pin 11 may be made of any 85 desired material it is preferred that the same be of copper.

From the foregoing description it is thought to be obvious that an automatic 90 gauge glass valve constructed in accordance with our invention is particularly well adapted for use by reason of the convenience and facility with which it may be as- sembled and operated, and it will also be 95 obvious that our invention is susceptible of some change and modification without departing from the principles and spirit thereof and for this reason we do not wish to be understood as limiting ourselves to the precise arrangement and formation of the several parts herein shown in carrying out our invention in practice except as hereinafter claimed.

100 We claim:

1. A nipple for an arm of a gauge glass having an intermediate portion formed with a substantially V-shaped offset, the outer end of said offset being provided with an 105 internal valve seat, a valve member freely 110

movable within the offset for coaction with the internal valve seat, a wall of said offset being provided with an opening of a diameter to permit the passage of the valve member therethrough, and means for normally closing said opening.

2. A nipple for an arm of a gauge glass having an intermediate portion formed with a substantially V-shaped offset, the outer 10 end of said offset being provided with an internal valve seat, a valve member freely movable within the offset for coaction with

the internal valve seat, a wall of said offset being provided with an opening of a diameter to permit the passage of the valve member therethrough, a plug for normally closing said opening, and a member carried by the plug and extending inwardly of the offset toward the internal valve seat to limit the movement of the valve member away 20 from said seat.

JOHN WALKER.
WESTON WALKER.
